No. 825,833.

PATENTED JULY 10, 1906.

R. L. HIGHT.
ELECTRIC CLOCK.
APPLICATION FILED AUG. 31, 1905.

UNITED STATES PATENT OFFICE.

ROBERT L. HIGHT, OF DECATUR, ILLINOIS.

ELECTRIC CLOCK.

No. 825,833.

Specification of Letters Patent.

Patented July 10, 1906.

Application filed August 31, 1905. Serial No. 276,593.

To all whom it may concern:

Be it known that I, ROBERT L. HIGHT, a citizen of the United States, residing at Decatur, in the county of Macon, State of Illinois, have invented certain new and useful Improvements in Electric Clocks, of which the following is a specification, reference being had therein to the accompanying drawings.

10 This invention relates to an electric clock, and particularly to a master-clock adapted to be electrically wound.

The invention has for an object to provide an improved construction and arrangement 15 of the electrically-controlled means by which the clock may be wound by a rotary motor having an intermittent motion, said motion being controlled by contact means carried on the shaft of the escapement-wheel.

20 A further object is to provide a magnetic friction-brake coöperating with a disk carried on the armature-shaft for controlling the extent of rotation of said shaft, said shaft being provided with means for positively 25 breaking the contact after each movement of the armature-shaft.

Other and further objects and advantages 30 of the invention will be hereinafter set forth, and the novel features thereof defined in the appended claims.

In the drawings, Figure 1 is a vertical section of the master-clock, taken on the line 1 1, Fig. 2, and shown in circuit with the preferred construction of secondary clock. Fig. 35 2 is a cross-section on the line 2 2, Fig. 1. Fig. 3 is a vertical section on the line 3 3, Fig. 2. Fig. 4 is a similar view on the line 4 4, Fig. 2. Fig. 5 is a vertical section on the line 5 5, Fig. 2; and Fig. 6 is a horizontal section 40 on the line 6 6, Fig. 2.

Like letters of reference refer to like parts throughout the several views of the drawings.

The clock-movement may be mounted in any suitable way well known in this art and 45 is controlled by the usual construction of pendulum A, as shown in Fig. 2, which is mounted at its upper end by means of the spring-plate A', secured to the post A² in the usual manner. This pendulum in its movement is adapted to engage the depending arm A³, carried by the shaft A⁴ of the escapement-wheel anchor A⁵, said shaft being suitably mounted to oscillate in the frame of the clock. The depending arm A³ is provided 55 with a lateral projection A⁶, adapted to contact with or be connected to the pendulum.

The anchor A⁵ coöperates with the escapement-wheel B, carried upon the winding-shaft B', which shaft is surrounded by a coil-spring B², secured at one end to a collar B³, 60 carried by said shaft, and at its opposite end to a collar B⁴, loosely mounted upon a stub-shaft and connected with the winding-pinion B⁵. This pinion meshes with a corresponding pinion B⁶, secured to the armature-shaft B⁷. The armature-shaft is provided with the armature C, surrounded by a field-magnet C' of ordinary construction, such as present in rotary electrical motors. The shaft B' is provided at the front of the clock-movement with the usual barrel-pinion D, 70 meshing with a driving-gear D', the latter being provided upon its shaft with a barrel-pinion D², meshing with a gear D³, carried upon a counter-shaft, said counter-shaft having thereon a barrel-pinion D⁴ and a gear D⁵, the latter meshing with a pinion D⁶, carried upon the shaft of the gear D⁷, which in turn meshes with the barrel-pinion D⁸ in the usual manner incident to clock-movements, as 80 shown by Fig. 1. By this means the movements of the hands of the clock are relatively controlled.

For the purpose of establishing electrical contact and energizing of the motor a contact-bridge C² is loosely mounted upon the driving-shaft B' and is rotated thereon by means of a pin or projection C³, carried by the collar B³ upon said shaft, so that in the rotation thereof the bridge C² is lifted and in its descending movement rests upon the parallel contact-plates C⁴, mounted on an insulating-block C⁷ upon the frame. The circuit from these contacts extends through the line E to one of the brushes C⁵ upon the armature-shaft B⁷, while the opposite brush is connected by means of the line E' with an electromagnet E² at the base of the motor, said magnet having the line E³ extending therefrom to the energizing-magnet of the secondary clock, as 90 shown in Fig. 1, the return-line E⁵ from said energizing-magnet being in circuit with the battery E⁶, if desired, and is connected by line E⁷ with the opposite contact-plate. By this means an intermittent current is allowed to pass through the motor, producing a similar motion thereof and winding the spring B² to sufficient extent to continue the driving of the escapement-wheel and coöperating parts. In order to determine positively the extent of travel of this motor and arrest the same without jar or vibration, the 100 105 110

armature-shaft is provided with a friction-disk F, secured thereto, as shown in Fig. 5, and adapted to coöperate with a friction brake-arm F', carried by the sleeve F², formed of magnetic material, and adapted to be attracted by the pole-piece F⁶, extending from the magnet E² at the base of the motor, the pole-piece F³ having an extension F⁴ entering a suitable recess in the sleeve F² to 5 guide its movement and being provided with the usual brass covering F⁵ to prevent sticking or adhesion of the parts while attracted toward each other. When the circuit is closed, the sleeve is attracted by the pole-piece F⁶ and drawn away from the disk F, thus placing the spring F⁷ under tension, and when the circuit is broken said spring forces the sleeve and brake-arm carried thereby into contact with the disk. It is also desirable to immediately break the contact between the bridge and plates after the movement of the motor, and this is accomplished by means of a pin G, carried by the pinion B⁶ and adapted to engage a lever G', carried 10 by the rock-shaft G², which shaft is provided with a restoring-spring G⁵ and carries at its forward portion an arm G³, disposed between the contact-plates C⁴ so as to engage the bridge C² and force the same off of the contact-points. 15

While the master-clock hereinbefore described may be used with any desired construction of secondary clock, still the form shown in Fig. 1 has been found particularly 20 advantageous and adapted to coöperate with the construction and arrangement of parts hereinbefore described. In this secondary clock the energizing-magnet H is in circuit with the lines E³ and E⁵, hereinbefore described, and is provided at each end with pole-pieces H', having disposed between the same an armature H², pivotally mounted and suitably weighted—for instance, by means of the extended arm and weight H³—25 so as to remove the pole-faces thereof from the pole-pieces H', as shown in Fig. 1. The shaft of this armature is also provided with an arm H⁴, carrying at its upper end a shuttle H⁵, adapted to coöperate with a series of 30 teeth or pins H⁶, carried by a minute-wheel H⁷, provided with the usual clock-gearing H⁸, controlling the hour and minute hands of the secondary clock. 35

In the operation of the invention the tension-spring B' is placed under sufficient tension to rotate the shaft of the escapement-wheel for one or more revolutions, and during this rotation the contact-bridge is lifted by the pin C³, carried by said shaft, and dropped 40 by gravity upon the plates C⁴, thus passing current to the motor, which by the rotation of its armature rewinds the spring on the shaft for one or more rotations. This armature-shaft has secured thereto the disk F, and in 45 its rotation with the shaft the pin G thereon

engages the lever controlling the rock-shaft G², the arm G³ of which at once forces the bridge out of contact with the plates, thus cutting off the current from the motor and permitting the brake-arm F' to engage the disk to limit the extent of movement of the motor and to arrest the same. The current when passing through the master-clock, as hereinbefore described, continues through the magnet H of the secondary clock, thus 50 oscillating the armature thereof and also the shuttle carried by said armature, so as to produce a step-by-step rotation of the minute-wheel therein, as the parts here shown are constructed and arranged to energize the motor of the master-clock and the magnet of the secondary clock once each minute. 55

The extension F⁴ from the pole-piece F³ not only guides the sleeve, but also causes the lines of force or magnetic flux to flow 55 from one pole-piece to the other through said extension, thereby causing the sleeve F² to be attracted to the pole-piece F³ with about three times its usual strength.

Having now described my invention and set forth its merits, what I claim, and desire to secure by Letters Patent, is—

1. In an electric clock, an escapement mechanism, an actuating-spring therefor, a rotary electric motor for intermittently rewinding said spring, current-controlling means for said motor carried by said escapement mechanism, and an automatic brake operatively connected to said motor and in circuit therewith and with the current-controlling means. 95

2. In an electric clock, a master-clock having an escapement mechanism, an actuating-spring therefor, a rotary electric motor for winding said spring, means carried by the escapement mechanism for intermittently completing circuit to said motor, a secondary clock, and a single circuit extending from said circuit-completing means to said motor and secondary clock. 105

3. In an electric clock, an escapement-wheel and anchor, a spring for actuating said wheel, an electric motor adapted to intermittently rewind said spring, a contact-bridge controlled by the shaft of said escapement-wheel, an armature-shaft for said motor provided with a brake member, a coöperating brake electrically released therefrom during the movement of the motor, and means controlled by said armature-shaft for positively moving said bridge and breaking circuit. 115

4. In an electric clock, an escapement-wheel and anchor, a contact-bridge loosely mounted upon the shaft of said escapement-wheel, a spring secured to said shaft, a projection carried by said shaft for rotating said bridge, separated contact-plates disposed in the path of travel of said bridge, and an electric motor in circuit with said plates and geared to rewind said spring. 125

5. In an electric clock, an escapement-wheel and anchor, a contact-bridge loosely mounted upon the shaft of said escapement-wheel, a spring secured to said shaft, a projection carried by said shaft for rotating said bridge, contact-plates disposed in the path of travel of said bridge, an electric motor in circuit with said plates, a projection disposed upon the armature-shaft of said motor, a 10 rock-shaft having a lever disposed in the path of said projection, and an oscillating arm at the opposite end of said rock-shaft disposed adjacent to said plates to engage and remove the bridge therefrom.
- 15 6. In an electric clock, a pendulum, an actuating-spring therefor, a rotary electric motor for rewinding said spring, means for intermittently feeding current to said motor, a brake-disk secured to the armature-shaft of 20 said motor, and a brake-arm coöperating with said disk.
- 25 7. In an electric clock, a pendulum, an actuating-spring therefor, a rotary electric motor for rewinding said spring, means for intermittently feeding current to said motor, a brake-disk secured to the armature-shaft of the motor, a brake-arm coöperating with said disk, a pole-piece for magnetically attracting said arm during the movement of said motor, 30 and means for holding said arm in contact with said disk at the termination of said movement.
- 35 8. In an electric clock, an escapement-wheel and anchor, a collar carried by the shaft of said wheel, an actuating-spring extending from said collar to a relatively fixed point, an electric motor, a gearing therefrom to the relatively fixed end of said spring for rewinding the same, a pin extending from said collar, a contact-bridge loosely mounted 40 upon the shaft of said escapement-wheel to be engaged and raised by said pin, and parallel contact-plates in circuit with said motor and disposed in the path of said bridge.
- 45 9. In an electric clock, an escapement-wheel and anchor, a collar carried by the shaft of said wheel, an actuating-spring extending from said collar to a relatively fixed point, an electric motor, a gearing therefrom to the relatively fixed end of said spring for 50 rewinding the same, a pin extending from said collar, a contact-bridge loosely mounted upon the shaft of said escapement-wheel, parallel contact-plates in circuit with said motor and disposed in the path of said bridge, an 55 oscillating arm disposed to travel into contact with said bridge, and means actuated by said motor for oscillating said arm.
- 60 10. In an electric clock, a rotary motor, a brake-disk carried by the shaft thereof, a 60 brake-finger adapted to contact with said disk, a slidingly-mounted armature disposed adjacent to a pole-piece from said motor, a coöperating member carried by the opposite pole-piece and provided with an extension 65 disposed under said armature, and a restoring-spring adapted to throw said finger into contact with said disk.

In testimony whereof I affix my signature in presence of two witnesses.
